(57) **CLAIM**

The ornamental design for a furniture article, as shown and described.

DESCRIPTION

FIG. 1 is a top perspective view of a furniture article, showing our new design;

FIG. 2 is a front elevation view thereof;

FIG. 3 is a right elevation view thereof;

FIG. 4 is a left elevation view thereof; and,

FIG. 5 is a top plan view thereof.

The mattress and side rails shown in broken lines are unclaimed environment, and form no part of the claimed design.

1 Claim, 5 Drawing Sheets
